ART OF BUOYANT GARMENT CONSTRUCTION

Application filed February 20, 1926. Serial No. 89,706.

One of the phases of this invention relates to improvements in that class of garments rendered buoyant by inclusion or addition of buoyant, fibrous material, and another phase of the invention comprehends the art or process of producing the garment.

10 Among the objects in view are the increasing in buoyancy and decreasing in actual weight of a garment and the saving of substantially all excess material, the saving of expense, the improvement in flexibility and capacity for conformity of the garment to body movements, and the production of a light, durable, comfortable garment having full capacity for floating the user.

A further object is the provision of a sufficiently buoyant garment to sustain the body of the wearer while possessing limpness equal substantially to the limpness of ordinary bathing suit fabric.

With these and other objects in view as will in part hereinafter become apparent and in part be stated, an embodiment of the structural features of the invention comprehends 25 a garment having one or more containers for buoyant fiber filled therewith to the point of distension substantially without excess filling or compression, whereby the fiber is left in a substantially open condition.

30 Those features of the invention comprehending the art or method assure the production of the garment with the fibrous material retained open and substantially only
35 sufficient fiber used to distend the container for such fiber substantially without compression or rendering the fiber compact.

The invention comprises certain other novel constructions, combinations and arrangements of steps of an art or process as will hereinafter become apparent and be subsequently set forth in the appended claims.

In the accompanying drawings.—

45 Figure 1 is a perspective view of a fragment of a garment in the course of being constructed in accordance with the present invention.

50 Figure 2 is a detail, perspective view of one of the filler devices segregated for clearness of disclosure, parts being shown in broken

lines for illustrating the preferred mode of use.

Figure 3 is a fragmentary, sectional elevation of a different form of apparatus for carrying out the invention.

Figure 4 is a perspective view of a garment made after and including an embodiment of the present invention.

Figure 5 is an enlarged, detail, fragmentary cross section taken approximately on the plane indicated by line 5-5 of Figure 4.

Figure 6 is a fragmentary, sectional perspective, the section being taken on the plane indicated by line 6—6 of Figure 4 and looking in the direction indicated by the arrow.

Figure 7 is a view similar to Figure 4 of a garment embodying the present invention, upper portions being broken away and non-buoyant trunks being indicated as surrounded by the buoyant skirt portion of the garment. 70

It has been proposed to make garments, such as bathing suits and life preservers, having fibrous buoyant elements. Various arrangements have been suggested, and, in the case of bathing suits, the most commonly proposed construction includes a bat or layer of buoyant fiber placed between two sheets of woven fabric and quilted or otherwise effectively stitched. Kapok or illana silk has been

proposed for use as the buoyant fiber in such structures, but from a series of tests we have repeatedly proven that any given area of a garment will displace approximately only one-fourth as much water (or, in other words, is only one-fourth as buoyant) as the same amount of the same fiber found in a given area of the garment when the fiber is open, that is, fully loosened up and spread out. In other words, where a quilted garment of the character just described has its areas divided into squares, and one of them is cut away and

into squares, and one of them is cut away and the fibrous material removed and opened fully, and then four similar squares are cut from the same garment and left in the initial condition, the opened fibrous material from the single square will usually float as much weight or more than can be floated by the four connected squares in the original condition. Thus it becomes obvious that the compressing 135

or compacting of the fiber incident to batting and quilting materially detracts from buoyance, consumes excess fibrous material (which is quite expensive), and produces a finished garment of considerably more actual weight than justified by the buoyancy attained.

In other instances of garment construction, buoyant material containers or pockets have been proposed, some intercommunicating and others independent, and in the instances of intercommunicating containers use of the objectionable bat of fibrous material has been suggested. In the instances of non-communicating containers, the suggestion has been for the use of the fibrous material in the form of a twisted wad or the packing of the fiber by a tamping instrument producing a condition of even greater compactness than in the instance of quilted bats. In all these proposed instances, buoyancy is reduced, cost of production increased over that which would have been the cost had only the approximate quantity of open fiber been utilized, the weight of the garment rendered excessive, and flexibility has been largely eliminated. Lack of flexibility is an objection even with life preservers, such as life belts, life jackets, and the like, but with bathing suits the compressed fiber in the containers rendering the garment as a whole stiff, board-like and unyielding is especially objectionable. In such proposed constructions there is no possibility of conformity to body movements, and this fact is accentuated in some forms of the proposed constructions wherein it has been suggested that tufts or protuberances be provided to cause the garment to contact with the body only at spaced points for facilitating donning and removing such garments.

All of these difficulties are overcome by the present invention in which substantially only the amount of open fiber necessary for retaining the containers distended is employed with practically no compression or packing of the fiber whatever so far as possible. The construction of a garment in this manner is rendered possible by the manner of delivery of the fiber to the containers, as will hereinafter appear, and would not be possible from the use of batting, wadding, or tightly tamped fiber.

Referring to the drawings by numerals, 1 indicates a body of a garment made in the form of a bathing suit having legs 2, all of the ordinary conventional contour and finish, so far as appearances are concerned, as the average popular bathing suit, except for the character of the material of which the suit is formed. Such material consists of two layers of fabric 3, 3, as best seen in Figures 5 and 6, stitched together at intervals, as seen at 4, 4, to form longitudinally disposed containers or pockets having the appearance in the finished garment of longitudinal fluting

or ribs 5. The tubes making up ribs 5 are preferably relatively slender, that is small in diameter, but, of course, may vary in size and proportions and in length and relative arrangement with respect to the body 1 of the garment, according to preference. Each tube making up a rib 5 is rendered distinct and separate from all other tubes by the stitching 4, as clearly seen in Figure 5, and each tube is supplied with buoyant, fibrous material, such as kapok or pachote, in an open condition, that is, in a condition in which the fibers are substantially free from crowding or packing. Some slight compactness may be unavoidable, but it is the intent and purpose of the present invention to avoid compactness as far as reasonably practicable, and it is this freedom from compactness of the fiber which is intended to be described by the word "open" as used throughout this specification and in the appended claims.

To enable the filling of the several tubes or containers making up the ribs 5 to the point of distention while retaining the fiber in open condition, special care must be exercised, and an essential feature of the present invention includes the art by which this result is obtained. In order to illustrate, so far as may be done by drawing, a preferred method of practicing the art, there is shown in Figures 1 and 2 structures well adapted to facilitate such practice. A supply hopper 6 of any appropriate size and shape discharges through a tube 7 and a rotary blower 8 into a distributing tube 9. The blower 8 is driven by any suitable source of power, such as an electric motor 10, and the shaft of the blower is provided with a pulley 11 engaged by a belt 12 extending to and actuating the shaft 13 of an opener 14 arranged in the lower portion of the hopper 6 for insuring opening of the fiber from the hopper just before it enters the tube 7. Any appropriate opener 14 may be utilized, and it is to be understood that a more effective mechanical operation of the opener 14 may be utilized, and it is to be understood that the more effective mechanical operation of the opener 14 in loosening up the discharging fiber the more acceptable will be the results obtained. The tube 9 may lead directly to a single discharge pipe, not illustrated, and has, in practice, been found to be very successful when so arranged. However, as a matter of saving in time and labor, it may be preferable to cause the tube 9 to communicate with a manifold 15 communicating with a series of discharge tubes 16. As many of the tubes 16 may be connected with the manifold 15 as may be found to successfully operate up to the point of having a tube 16 for each of the tubes of the garment 1. One end of each of the tubes making up the ribs 5 is closed, as, for example, the upper end, as by stitching or otherwise as may be preferred, while the opposite end is left open by leaving

the lower terminus of the two pieces of fabric 3, 3, unattached, thus leaving a flap 17 hanging loose and a shorter flap 18 also loose which are adapted to be connected upon the 5 completing of the filling of the several containers or tubes making up the ribs 5. Each flexible tube 16 is provided at its free end preferably with a quickly detachable union 19 adapted to be hermetically locked to a 10 nozzle 20. Each nozzle 20 consists of a relatively short tube, as seen best in Figure 2, having a troughlike extension 21 of a length preferably equal to the length of the respective garment tube or container making up the 15 respective rib 5 into which the trough 21 is to be introduced. While the trough 21 is shown as formed of substantially one-half of a tube, that is, the trough is substantially semi-circular in cross section, a greater or 20 less are than a semi-circle may be provided, and each trough 21 may, in fact, be almost a complete tube with only a longitudinal slot extending along its upper portion for enabling manipulation of the parts as herein- 25 after described.

To fill the tubes making up the ribs 5, a troughlike extension 21 from a nozzle 20 is inserted in the garment tube or container for practically the full length thereof, after the 30 manner indicated in Figure 1, and where the tubes 16 are supplied in multiple, a troughlike extension 21 is inserted in each of the tubes of the garment. The insertion is made up to the point where the nozzle 20 extends 35 within the tube of the garment after the manner indicated in Figure 2. As the filling of the several garment tubes is a mere duplication of the filling of one, one only will be described. After the troughlike extension 21 40 is in place, as stated, the mechanism described is turned on and the blower 8 delivers open fiber through the nozzle 20. The air which accompanies the fiber keeps the fabric 3 above the open portion of trough 21 distended and the fiber slides out along the 45 trough 21 to the end of the trough, that is to the end of the garment tube in its open condition, and care should be exercised to watch the filling process so as to avoid possibility 50 of any undue compressing or compacting of the fibrous material by allowing the machine to operate after the tubes have been filled. Just as soon as the tube is full, the motor 55 is stopped, and an appropriate instrument 10 is pressed down on the fabric of the garment tube at the open end thereof, that is, across the end of the nozzle 20 into the trough 21 after the manner indicated by the thumb 22 seen in Figure 2. Any other instrumentality 60 susceptible of doing the work of the thumb may be substituted therefor. The thumb or other instrument having been thus inserted into the trough 21, the nozzle 20 with its troughlike extension 21 is withdrawn from 65 the garment, leaving the fiber within the gar-

ment tube in its open condition and with the garment tube distended after the manner seen in Figure 5. Withdrawal of a number of nozzles 20 simultaneously may be effected by the use of a comb-like instrument with a tooth 70 of such comb for each nozzle shaped, proportioned, and adapted for functioning after the manner of the thumb seen in Figure 2.

It is to be observed that after the several garment tubes making up the ribs 5 have 75 been thus filled and the filling instrument removed, the flap 17 which is preferably pendent from the outer fabric of the garment is folded inward and stitched at 23 to close the lower or formerly open ends of the 80 several fabric tubes. This closing action is preferably done in a manner to leave an open space 24 communicating with all of the several fabric tubes so that space is provided for expansion of the fiber incident to becoming moist or to use of the garment.

Because of the character of the fibrous filling of the several containers or fabric tubes of the garment, the walls of the garment are found to be laterally elastic to a considerable 90 degree, that is to say, the garment can be stretched in a sidewise direction with respect to the ribs 5 somewhat after the manner of jersey cloth or knitted goods. Also, the character of filling leaves the garment 1 a very 95 large degree of flexibility in every other direction, so that the garment will readily conform to the outline of the body and respond easily to body movements, and at the same time throughout many tests the garment has 100 proved beyond question its effective buoyancy and capacity for permanently sustaining the body of the wearer in a floating condition in water.

The garment 1, of course, is susceptible of 105 being made up in any form or shape according to any style or requirement desired by the user. In Figure 7 is illustrated a similar garment at 1' having a skirt portion 2' in lieu of the leg portions 2, and in which 110 skirt portion is secured the ordinary trunks 2" of the conventional bathing suit. Obviously, while the trunks 2" are shown as of the usual non-buoyant type, they may be otherwise constructed, and every conceivable 115 variation may be indulged in the matter of suit construction for body garments for purposes herein indicated within the intent, meaning and purpose of the present invention.

Furthermore, it is entirely possible to fill the fabric tubes of the garment with open fiber in other ways than that just described, as, for example, after the manner indicated in Figure 3, in which the hopper 6' having 125 the opening mechanism 14' is shown as arranged with its discharge tube 17' formed directly with a nozzle 20' extending into the fabric tube 5'. An injector nozzle 25 extends into the nozzle 20 in position for de- 130

liveling blasts of compressed air or other pressure fluid for drawing the fiber from the tube 17' and discharging the same into the fabric tube 5' in an open condition. This particular apparatus is especially well adapted for use for filling fabric tubes which are comparatively short.

Other methods of filling fabric tubes with fiber in an open condition are entirely practicable, such, for example, as the filling of the same by hand by first carding the fiber into a condition of long, thin, open curls, and then drawing the curls into the fabric tubes by passing therethrough boddkins to which the curls of fiber are attached.

The structure of the garment and its conformity to styles are not subject to any appreciable restriction or limitation whatever, because of the presence of the buoyant containers, owing to the flexibility thereof. Furthermore, the open condition of the fiber assures ready and quick drying after use of the garment, and also enables the garment to be easily and effectively packed for shipment in a rolled or folded condition. While the parallel seams 4 are shown as connecting the two sheets of fabric 3, 3, to form the garment tubes or containers, such tubes may obviously be otherwise formed if desired. The making of the garment 1 is almost as simple an operation as that of the construction of an ordinary bathing suit, and no special provision is required for facilitating donning or removing the garment. The structure as shown in the drawings includes shoulder straps 26, 26, with button-holes and buttons 27 for facilitating attachment and detachment and enabling easy removal or putting on of the garment. The fabric 3, 3 is preferably of appropriate soft, woven material and substantially non-elastic, but may be of any other suitable material, such as jersey or knitted goods, and will vary in thickness and other characteristics according to the wishes of the user. The structural features of the garment lend themselves effectively to the use of silk as the outer fabric 3, since the presence of the buoyant fiber precludes the objection heretofore raised to the use of silk in too close adherence to the flesh of the wearer.

What is claimed is:—

1. A buoyant garment comprising a body of fabric stitched to form a series of tubes, and open, buoyant fiber within and distending the walls of the tubes, the tubes having a place of intercommunication initially free from fiber for allowing expansion of the fiber.
2. The art of constructing buoyant garments comprising forming a fabric body with a container and pneumatically filling the container with buoyant fiber.
3. The art of constructing buoyant garments comprising forming a fabric body

with a container and pneumatically filling the container with buoyant fiber in the presence of a rigid guide for the fiber.

4. The art of constructing buoyant garments comprising forming a fabric body with a container and pneumatically filling the container with buoyant fiber in the presence of a rigid guide for the fiber, and withdrawing the guide while retaining the fiber in the container.

In testimony whereof we affix our signatures,

ERNEST W. BLACK.
GEORGE L. HALL.
